UNITED STATES PATENT OFFICE.

ROY P. SMITH, OF WICHITA, KANSAS.

BOOK AND COPY HOLDER.

Application filed March 26, 1928. Serial No. 264,603.

This invention relates to an especially designed holder for books and the like.

The purpose of the invention is to provide a convenient and dependable device where-
5 by the book may be held in proper and convenient position for reading or making copies.

I propose a device of this class which is especially suitable for holding the book in
10 an inclined reading position, the device including means which is readily adjustable for retaining the leaves open.

The precise details as well as their arrangement and association will become more
15 readily apparent from the following description and the accompanying drawings.

In the drawings,—

Figure 1 is an end elevational view of a book holder, constructed in accordance with
20 the present invention.

Figure 2 is a front view of the same.

Figure 3 is a bottom view taken approxi-
25 mately on the plane of the line 3—3 of Fig-
ure 1.

Figure 4 is a longitudinal sectional view,
30 taken approximately on the plane of the
vertical line 4—4 of Figure 1.

Referring now to the drawings by refer-
ence numerals, it will be observed that 1 des-
35 ignates a heavy metallic base carrying an up-
right or standard 2 having lower vertical
portions and an upper inclined portion.
The inclined portion is appropriately fas-
tened to the rear side of a rearwardly in-
40 clined backing plate 3, of the holder proper.
This holder is formed from sheet material
bent to provide the backing plate 3 and to
provide a right angularly disposed ledge or
shelf 4. The shelf is formed with trans-
45 verse slots 5, disposed at longitudinally
spaced points.

Associated with the shelf and the slot is
a book retaining device, which is adjustably
mounted. This device comprises a metal
50 bar having a horizontal portion 6 disposed
beneath the shelf and having upturned ends
7 which extend up through the slots 5, these
being shaped as shown in Figure 1, to pro-
vide a pair of spaced leaf grips. The cen-
55 tral section of the bar 6 is fastened to the
intermediate portion of adjusting means.
The means comprises a slidably mounted rod
8, whose end portions slide through guides
9 and 10, fastened to the under side of the
60 shelf. The outer end of this rod 8 is bent
down as at 11, to form handles. In addi-

tion, I provide a retention spring 12, which as shown in Figure 3, has one end anchored to one of the guides, and has its opposite ends fastened as at 13, to the rod 8. The 60 tension of the spring is such as to normally hold the bar and grips in the position shown in Figure 1.

It is obvious that by catching hold of the handle 11 and sliding the rod 8 outwardly, 65 the grips 7 are moved away from the back-
ing plate to permit the books to be placed in
position on the shelf. Then, by releasing
the rod, the spring forces the grip into
yieldable contact with the leaves of the book, 70 holding the halves or portions of the book
open to facilitate reading.

It is obvious from the description and
drawings that I have evolved and produced
a simple and inexpensive contrivance, which 75 is especially suitable for holding a book or
the like in an inclined position to facilitate
reading or copy work. The simplicity of
the invention is such as to permit a clear
comprehension of the advantages and fea- 80
tures to be had. Therefore, a more lengthy
description is regarded unnecessary.

Minor changes in shape, size and rear-
rangement of details coming within the
field of invention claimed may be resorted 85
to, if desired.

I claim:

1. In a book holder of the class described,
a base, a standard rising from said base, a
backing plate fastened to said standard, said 90
backing plate having an angularly disposed
book supporting ledge at its bottom, said
ledge having longitudinally spaced trans-
versely disposed slots formed therein, a hori-
zontal bar disposed beneath said ledge and 95
having its opposite ends bent upwardly and
extending through said slots to provide a
pair of book grips, an operating means for
said bar, and spring retaining means asso-
ciated with the bar. 100

2. In a book holder of the class described,
a base, a standard rising from said base, a
backing plate fastened to said standard and 105
including a horizontal ledge, said ledge hav-
ing transversely disposed longitudinally
spaced slots formed therein, a horizontal
bar disposed beneath said ledge and having
upstanding ends extending through said 110
slots and functioning as book grips, a pair
of guides mounted on the bottom of the
ledge, a rod slidably in said guides and con-
nected with the central portion of the bar.

3. In a book holder of the class described, a base, a standard rising from said base, a backing plate fastened to said standard and including a horizontal ledge, said ledge having transversely disposed longitudinally spaced slots formed therein, a horizontal bar disposed beneath said ledge and having upward ends extending through said slots and functioning as book grips, a pair of

10 guides mounted on the bottom of the ledge,

a rod slidable in said guides and connected with the central portion of the bar, together with a spring attached at one end to one of said guides and at the opposite end to the intermediate portion of said rod, whereby to hold said grip in yieldable contact with the leaves of the book. 15

In testimony whereof I affix my signature.

ROY P. SMITH.
